(57) **CLAIM**

The ornamental design for a cover for electric motor, as shown and described.

DESCRIPTION

FIG. 1 is a perspective view of a cover for electric motor showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof; and,

FIG. 8 is a perspective view thereof at an installed position, portions of the view shown in phantom forming no part of the design.
